CLAIM

The ornamental design for a trash bag holder, as shown and described.

DESCRIPTION

FIG. 1 is a perspective view of a trash bag holder showing my new design;

FIG. 2 is a front view thereof;

FIG. 3 is a back view thereof;

FIG. 4 is a left view thereof;

FIG. 5 is a right view thereof;

FIG. 6 is a top plan view thereof;

FIG. 7 is bottom plan view of a trash bag holder thereof; and,

FIG. 8 is an enlarged view of portion of FIG. 1.

The broken lines in the figures are to show enlarged areas and form no part of the claimed design.

1 Claim, 8 Drawing Sheets
